UNITED STATES PATENT OFFICE.

JOHANNES NADROWSKI, OF DRESDEN, GERMANY.

TURBINE WHEEL.

SPECIFICATION forming part of Letters Patent No. 702,461, dated June 17, 1902.
Application filed December 19, 1901. Serial No. 86,588. (No model.)

To all whom it may concern:

Be it known that I, JOHANNES NADROWSKI, a subject of the King of Prussia, Emperor of Germany, residing at Dresden, Kingdom of Saxony, Germany, have invented certain new and useful Improvements in Turbine Wheels, of which the following is a description.

The turbine wheels hitherto in use are constructed on the water-wheel system, with the modification that in view of the nature of the driving power the wheels were made very small and the blades arranged close together. It is, however, necessary in the case of wheels running at a very high speed, as with the "De 5 Laval" steam-turbines, to take into consideration the strain put upon the wheel, owing to the centrifugal force, and this involves difficulties in the construction of such wheels which it is the object of the present invention to remove.

In order to render the present specification easily intelligible, reference is had to the accompanying drawings, in which similar letters of reference denote similar parts throughout the several views.

Figure 1 is a part facial elevation of a wheel constructed according to the present invention; Fig. 2, a sectional plan of the same; Fig. 3, a diagram (horizontal section through wall 30 between two channels) showing the arrangement of plates forming a modification of the wheel shown in Figs. 1 and 2. Figs. 4 and 4^a are part-sectional elevation and sectional plan of a further modification, and Figs. 5, 5^a, and 35 5^b are respectively part end and facial elevations and sectional plan of yet another modification.

The wheel is formed of a number of thin metal sheets recessed or perforated around their edges, the said sheets or disks being coaxially mounted and having their recesses or orifices slightly displaced as regards each succeeding sheet or disk, so that the whole set of sheets or disks when fixed together will 40 present a ring of recesses or orifices on or

through the whole disk in a direction inclined to the longitudinal axis of the shaft on which the wheel is mounted.

Referring to Figs. 1 and 2, the disks *a* are placed together, as above explained, with their orifices displaced, as at *a'*, and the whole set of disks are clamped together between the cheeks *c* and fitted in any suitable manner to the shaft *b*. When the disks, as in Figs. 1 and 2, are provided with a ring of orifices, a 50 peripheral ring *d* may be employed to hold the edges of the disks firmly together. It will be obvious that a wheel of this construction will be very strong, owing to the fact that the centrifugal force will only produce 55 radial and annular tension in the separate disks. The disks are advantageously of thin steel plate.

In the modification shown at Fig. 3 the thickness of the individual disks may be varied—for instance, the inner plates may be of greater thickness. In Figs. 4 and 4^a the arrangement is such that only a very fine edge is presented to the driving medium entering the outside disks, having outwardly-turned 60 lips to guide the steam into the channels. In Figs. 5, 5^a, and 5^b the construction of the wheel is similar to that of the Pelton wheel, allowing of a division of the rays at the central plane of the wheel. 75

I claim as my invention—

A turbine wheel composed of a series of thin metal plates having a series of channels around their edges, clamping-cheeks to hold said plates together and means for attaching 80 the whole to a driving-shaft, a peripheral ring to support and close around the edges of all the plates in the manner and for the purpose substantially as described.

In witness whereof I have hereunto set my 85 hand in presence of two witnesses.

JOHANNES NADROWSKI.
